UNITED STATES PATENT OFFICE

ALEXANDER O. HOEFTMANN, OWEN A. MCNAMEE, AND JAMES J. MORRISON, OF WORCESTER, MASSACHUSETTS, ASSIGNEES TO THE AMERICAN STEEL AND WIRE COMPANY OF NEW JERSEY, A CORPORATION OF NEW JERSEY

METHOD OF SHIPPING CABLE

Application filed June 11, 1931. Serial No. 543,703.

Our invention relates to a method and apparatus for loading and shipping submarine cables and the like in railroad cars, one of our objects being to load and ship cables in 5 cars in a safe and convenient manner. Another object is to enable the loading and shipping of a long cable in cars which individually have not the carriage capacity to accommodate this cable. A further object is to 10 provide, in a railroad car, apparatus for aiding the accomplishment of the above named and other objects. Other further objects may subsequently appear.

In the drawings:

15 Figure 1 is a sectional top plan view of a plurality of railroad gondola cars loaded with a submarine cable and ready for shipment, this being done in accordance with our invention.

20 Figure 2 is a cross sectional side view of these cars.

Figure 3 is an enlarged cross sectional side view of two adjacent ends of these cars.

25 Figure 4 is an enlarged cross sectional end view of one of these cars.

Having reference to these drawings, railroad gondola cars A are each furnished with a wood lining 2 which covers its floor and side walls, and an elongate round ended 30 straight sided wood form 3 which is centrally positioned in the car's interior and spaced from the lining over its side walls, an elongate substantially annular stowage space extending the car's length being thus provided.

35 Each end of each car is provided with an upstanding standard or support 4 from which a spring 5 is suspended, a cable holding clamp 6 being fixed to the free end of this spring.

40 These gondola cars are all coupled together, and plates 7 are bolted over the pins in their respective couplings to prevent uncoupling while en route. The submarine cable 8 is too long and heavy for carriage by 45 a single car. An end car is, therefore, loaded to its capacity with a part of this cable 8 by laying the same in the stowage space provided in that car in successively ascending elongate coil layers. The cable is passed 50 from the top coil layer of this car to an ad-

jacent car, which is then loaded to its capacity in a similar manner to the first named car. To prevent damage to the cable, a lazy loop 9 is formed in it where it passes from car to car, this loop being held by the cable holding clamps 6 to prevent it falling between the car ends. This permits slight movement of the car ends during transit without causing damage to the cable, the springs 5 allowing the loop a sufficient degree of flexible 60 movement. The cable is loaded in substantially a similar manner into successively adjacent cars until it is all loaded, the number of cars necessarily depending on the relative length and weight of the cable. The car's tops are then each covered over with boarding 65 10 to prevent injury to the cable, the lazy loops of the cable being preferably wrapped with burlap or the like as a protective measure.

If the cable is small enough to be carried by a single car a gondola car may be furnished and loaded in the manner just described, except that the supports 4 and their associated elements are not necessary as each 75 car will comprise a unitary load. The cars, of course, need not necessarily be inter-coupled in this instance, and even if they are coupling locking means will not be required.

By using our cable loading and shipping 80 method and apparatus any desired length of cable may be made complete at the mill making the same as it may be shipped thereby in a single length. Thus the necessity of making joints at the place the cable is laid 85 is to a great extent eliminated. Better joints or splices are made at the mill and much time is saved. Further, the labor cost of loading is reduced, and a high degree of safety is maintained during shipment.

90 Although we have shown and described specific forms of our invention in accordance with the patent statutes, we do not intend to limit the scope of our invention exactly thereto, except as defined by the appended claims.

We claim:

1. The method of loading and shipping a cable in railroad cars, consisting in furnishing the cars with a form constructed and ar- 100

ranged to provide a substantially annular stowage space, and laying the cable in coils in said spaces.

2. The method of loading and shipping a cable in railroad cars, consisting in furnishing the car with a form constructed and arranged to provide elongate annular stowage spaces extending the car's length, and laying the cable in said spaces in successively ascending horizontal elongate coil layers.

3. The method of loading and shipping a cable in a railroad car, consisting in furnishing the car with a lining and form constructed and arranged to provide an elongate annular stowage space extending the car's length, laying the cable in said space in successively ascending elongate coil layers, and fitting a covering over the top of the car so as to protect the coiled cable.

4. The method of loading and shipping a cable of too great a length and weight for carriage by a single car, consisting in coupling a plurality of cars together, furnishing each car with a form constructed and arranged to provide a substantially annular stowage space, and laying the cable in the spaces so provided and from one car to another.

5. The method of loading and shipping a cable of too great a length and weight for carriage by a single car, consisting in coupling a plurality of cars together, furnishing each car with a form constructed and arranged to provide a substantially annular stowage space, loading an end car with a part of the cable by laying successively ascending coil layers of the same in the stowage space provided in that car, passing the cable in lazy loop fashion from the top coil layer in the first named car to the bottom of an adjacent car and loading this car similarly to the first, and continuing to load the cable in successively adjacent cars and in substantially the manner described until all of it is loaded.

6. The method of loading and shipping a cable of too great a length and weight for carriage by a single car, consisting in coupling a plurality of cars together, furnishing each car with a form constructed and arranged to provide a substantially annular stowage space, loading an end car with a part of the cable by laying successively ascending coil layers of the same in the stowage space provided in that car, passing the cable in lazy loop fashion from the top coil layer in the first named car to the bottom of an adjacent car and loading this car similarly to the first, resiliently supporting the lazy loop in the cable against dropping between the car ends, and continuing to load the cable in successively adjacent cars and substantially in the manner described until all of it is loaded.

7. The method of loading and shipping a cable of too great a length and weight for carriage by a single car, consisting in coupling

a plurality of cars together, locking these cars against uncoupling, furnishing each car with a form constructed and arranged to provide a substantially annular stowage space, loading an end car with a part of the cable by laying successively ascending coil layers of the same in the stowage space provided in that car, passing the cable in lazy loop fashion from the top coil layer in the first named car to the bottom of an adjacent car and loading this car similarly to the first, and continuing to load the cable in successively adjacent cars and in substantially the manner described until all of it is loaded.

8. The method of loading and shipping a cable of too great a length and weight for carriage by a single car, consisting in coupling a plurality of cars together, locking these cars against uncoupling, furnishing each car with a form constructed and arranged to provide an elongate annular stowage space extending the car's length, loading an end car with a part of the cable by laying successively ascending elongate coil layers of the same in the stowage space provided in that car, passing the cable in lazy loop fashion from the top coil layer in the first named car to the bottom of an adjacent car and loading this car similarly to the first, resiliently supporting the lazy loop in the cable against dropping between the car ends, continuing to load the cable in successively adjacent cars and substantially in the manner described until all of it is loaded, and fitting covers to the cars to protect the cable.

9. In a railroad gondola car, an upstanding support at each end thereof, resilient cable holding means carried by said supports, and an elongate round ended form within and spaced away from the walls of said car.

10. In a railroad gondola car, an upstanding support at each end thereof, resilient cable holding means carried by each of said supports, a lining covering the interior of said car, and an elongate round ended form centrally positioned within said car and spaced away from the lining covering the upstanding walls thereof.

In testimony whereof, we have hereunto set our hands.

ALEXANDER O. HOEFTMANN.
OWEN A. McNAMEE.
JAMES J. MORRISON.
